UNITED STATES PATENT OFFICE.

THOMAS SHELDON, OF ENFIELD, CONN., ASSIGNOR TO HIMSELF AND HENRY INMAN, OF PORTLAND, AND E. P. FURLONG, OF WESTBROOK, ME.

IMPROVEMENT IN LIFTING-JACKS.

Specification forming part of Letters Patent No. 55,430, dated June 5, 1866.

To all whom it may concern:

Be it known that I, THOMAS SHELDON, of Enfield, in the State of Connecticut, have invented a new and useful Lifting-Jack for Carriages, &c.; and I hereby declare the following to be a full, clear, and exact description thereof, which will enable others to make and use my invention, reference being had to the accompanying drawings, forming part of this specification, in which is shown a side elevation of my invention, representing the different portions thereof.

In the accompanying drawings, A represents an upright secured to the base B and fitted with the cap. C D represent a sliding arm having the lip a and the attachment e, having a slot which embraces the upright A. The sliding arm D bears the head h, to receive the weight to be raised.

L indicates the hand-lever. b represents a brace composed of two parts attached at one end to either side of the cap C by the pivot P, at the other, on both sides of the lever L, by the pivot o.

E shows a horizontal sliding piece connected with the lever L by the joint n, and having two slots, one at r to receive the upright A, the other at s, through which the sliding arm D passes as it is raised or lowered.

H shows a rest or support for the sliding arm D'. The rest slides up or down upon the upright A by means of a slot similar to that in the attachment e. The slots in the horizontal sliding piece E, attachment e, and rest H are all made slightly larger than the upright A and the sliding arm D, over which they pass

and work loosely, in order that when a weight is imposed upon the head h they will bind them, and thus hold the weight stationary at any desired height; and the greater the weight the firmer it is by these means held.

When the hand-lever L is turned downward to its utmost extent the straight part t thereof will be parallel with the upright A, the part t resting against the upright A. In this position, as the pressure of the weight is in a vertical line passing through the center of the pivots P and o, it is evident that no amount of pressure upon the head h can raise the hand-lever and depress the head h. By this simple arrangement any weight can be securely sustained.

As the hand-lever is raised and lowered the brace b swings outward and backward. When the sliding arm D is raised and a weight resting thereupon the rest H is slipped up, so that the attachment e is brought in contact therewith. This will sustain the weight while the lever is again raised, the slide E thereby lowered, and the weight can then be lifted to any additional desired height. The lip a is designed for carriages whose axles are near the ground, such as "jiggers."

What I claim as my invention, and desire to secure by Letters Patent, is—

A lifting-jack, as herein described, and combining the various parts in the manner and for the purposes set forth.

THOMAS SHELDON.
